UNITED STATES PATENT OFFICE.

MITCHELL BURDINE ARENDELL, OF McALESTER, OKLAHOMA.

PESSARY.

1,113,083.

Specification of Letters Patent.

Patented Oct. 6, 1914.

Application filed June 25, 1913. Serial No. 775,748.

To all whom it may concern:

Be it known that I, MITCHELL BURDINE ARENDELL, a citizen of the United States, residing at McAlester, in the county of Pittsburg and State of Oklahoma, have invented certain new and useful Improvement in Pessaries, of which the following is a specification.

The present invention relates to improvements in pessaries, and is designed for the purpose of providing a sanitary surgical instrument especially as a support in cases of prolapsus or displacement of the uterus, ovarian congestion or dilation of the uterine canal. One of the greatest objections to the use of many of the devices now in vogue for this and analogous purposes is the unsanitary condition surrounding the instruments, and this objection is overcome by the use of my novel provision of means for drainage of the organ.

The primary object of the invention is the provision of a simple and inexpensive, but thoroughly efficient instrument for the purpose, and one that may be cleansed thoroughly and readily.

The invention consists essentially in an instrument of this character having special construction rendering it elastic to perform its required function and in the combination of drainage means for the instrument.

In the accompanying drawings I have illustrated one complete example of the physical embodiment of my invention, constructed according to the best mode I have so far devised for the practical application of the principles of the invention.

In the accompanying drawings: Figure 1 is a top plan view of an instrument embodying my invention. Fig. 2 is an elevation of the device. Fig. 3 is another elevation taken at right angles to Fig. 2. Fig. 4 is an enlarged sectional view taken on line 4—4 of Fig. 1.

In the preferred embodiment of my invention, I employ the stem 1 which is of gutta-percha or hard rubber, and the stem

is formed with prongs 2, 3, which at their respective ends are formed with enlargements or protuberances 4 and 5. The upper 50 end of the stem is cylindrical in cross section, with the addition that it is fashioned with a dovetailed lug or boss 6 complementary with a similar slot 7 in the head 8. The head 8 is also of hard rubber and is 55 fashioned with a central opening 9 extending therethrough and of greater diameter than the cross area of the stem. The slot 7 is undercut from the central opening 9 and the head incloses the end of the stem 60 and its lug. The head and lug are secured together by a metal screw 10, and the outer end of the opening for the screw is closed by a gutta-percha or hard rubber plug 11. The presence of the hard hubber plug eliminates 65 the possibility of oxidation of the metal screw.

The use of the instrument will be understood by those skilled in surgery, it being sufficient to state that the elastic prongs are 70 held together when the instrument is inserted into the organ and allowed to distend after insertion. The opening 9 provides an efficient means for drainage, and the instrument in actual use has proven highly satisfactory in correcting displacements and in affording a support in case of prolapsus.

Having thus fully described my invention, what I claim as new and desire to secure by Letters Patent is:

A pessary including in combination a forked elastic stem formed at one end with a dovetail locking lug, a disk formed with a large central opening and a slot complementary to the lug, and a screw passed 85 through the adjacent portions of the disk and lug.

In testimony whereof I affix my signature, in presence of two witnesses.

MITCHELL BURDINE ARENDELL.
